CLAIM

The ornamental design for a display system, as shown and
described.

DESCRIPTION

FIG. 1 is a front perspective view, showing the new design;
FIG. 2 is a rear perspective view, showing the new design;
FIG. 3 is a front elevation view of the display system of FIG.
1;
FIG. 4 is a rear elevation view of the display system of FIG.
1;
FIG. 5 is a left-side elevational view of the display system
of FIG. 1, the right-side elevational view being a mirror
image thereof;
FIG. 6 is a top plan view of the display system of FIG. 1;
FIG. 7 is a bottom plan view of the display system of FIG.
1;
FIG. 8 is a front perspective view, showing the engagement
of the peripheral bar assembly with a video monitor of the
display system of FIG. 1; and,
FIG. 9 is a rear perspective view, showing the engagement
of the peripheral bar assembly with the bottom of the video
monitor of the display system of FIG. 1.
The broken lines showing the displayed image in FIGS. 1,
3 and 8 depict environmental subject matter only and form
no part of the claim; while all other broken lines depict
portions of the display that form no part of the claimed
design.

1 Claim, 7 Drawing Sheets
